UNITED STATES PATENT OFFICE.

EARL B. DECKER, OF CLEVELAND, OHIO, ASSIGNOR TO BARTON R. DEMING, OF CLEVELAND HEIGHTS, OHIO.

IRONING MACHINE.

Application filed November 25, 1922, Serial No. 603,215. Renewed November 3, 1926.

The present invention relates to an ironing machine, and is more particularly directed to the construction by which the driven roller is brought into contact with the 5 stationary ironing member in a manner so as to provide equal pressure between the roller and the ironing member along all portions of contact between these two members. Other features of construction will be apparent as 10 the description proceeds.

Referring to the drawings, Fig. 1 is a perspective view showing the ironing machine; Fig. 2 is a rear view of a portion of the machine with parts in section; Fig. 3 is a 15 perspective view of the rear of the machine with certain parts broken away; Fig. 4 is a perspective view showing a part of one end of the machine; Fig. 5 is a perspective view showing an equalizing member forming part 20 of the roller operating member; Fig. 6 is a sectional elevation of a portion of the equalizing member.

Referring to the drawings, 1 indicates a table which is supported by legs 2, four in 25 number, these legs at the front being joined by means of a cross member 3 and at the side by means of cross members 4.

Mounted upon the table is an ironing member 6 which has a concave inner surface 30 7 and at its end is supported by suitable brackets 8 and 8^a. The ironing member 6 may be heated in any desired manner, being preferably hollow for the insertion of the heating element, such as a gas pipe 9, as 35 shown in Fig. 3.

Mounted to co-operate with the ironing member 7 is a roller 11, this roller being supported at both of its ends. At one of its ends it is supported by means of an arm 12, 40 the arm being movable through a slight radius so as to move the roller 11 toward and from the ironing member 6.

The roller member is preferably driven by means of gearing, such as indicated at 10 45 in Fig. 2. This forming no part of the present invention, further description will not be given.

The opposite end of the roll is provided with an extending shaft portion 11^a which 50 co-operates with a U-shaped arm 12^a. The arm at one end is provided with a half-bearing portion 12^b in which the shaft 11^a is journalled, and this half bearing is provided with a suitable cover 12^c which may be of 55 any construction.

The arm 12^a is carried by a shaft 13, the arm being pivotally connected by a tongue and groove connection as indicated at 14 in Fig. 2.

This mounting of the arm 12^a permits the 60 arm 12^a to be swung outwardly, and when in this condition the end of the roller 11 is free so that a circular garment, as for instance, a skirt, may be put over the end of the roller 11, or removed therefrom after the ironing 65 operation.

The pivotal connection at 14 between the shaft 13 and the arm 12^a is such that when the shaft 13 is turned the arm 12^a will be moved in a manner to raise the roller 11 70 toward the ironing member 6 or away therefrom.

It will be noted that the arm 12^a is U-shaped, or it may be described as having a 75 reentrant opening beneath the roller member 11, so that this leaves the end of the roller in what may be termed open ended condition, in that the arm is so fashioned as to permit a short band or a collar or something 80 of this character to be run between the roller member and the ironing member at the end of the roll 11, and even if the piece to be ironed in this fashion be fairly long, it will 85 be seen that the end of the piece which is run through the ironing member may pass down into the reentrant portion of the arm 12^a.

The shaft 13 is mounted in a suitable bearing 15 carried by the end member 8, and at 90 its opposite end is mounted in a closed collar 16 which collar is carried by the ironing member 6 or any portion which is adjacent thereto. There is also a shaft 17 upon which the arm 12 is mounted. This shaft has a bearing at 18 in the support 8^a, and at its 95 opposite end it is also mounted in the collar 16. As will be seen from Fig. 2, the two shafts 13 and 17 practically abut each other within the collar 16, so that both are supported, but yet both are free to turn independently.

Upon the shaft 17 there is an arm 19, and upon the shaft 13 there is an arm 20. Each 100 of these arms extends rearwardly and there is pivotally connected at the end of the arm 19 one end of a link 21, while similarly there is pivotally connected at the end of the arm 20 one end of a link 22. These link members are fastened to two points of an equalizing plate or equalizing member 23. This 105 equalizing plate has another opening which 110

receives a rod 24 which in turn is pivotally mounted upon an arm 25 which arm is secured at its end in substantially the middle portion of a shaft 26 which shaft extends transversely between the rear legs 22 which have before been described. At each end of the shaft 26 there are forwardly extending arms 27 and 28, these arms extending near the front forward legs 2. Mounted at the end of these arms is a treadle 29. This treadle member is pivotally mounted upon the arms 27 and 28. At the ends of the arms 27 and 28 there are ratchet members 30 and 31 and these ratchets co-operate with teeth 32 which are formed upon or carried by the inner surface of each of the front legs 2. These pawls are thrown out of engagement by means of the treadle 29, and for this purpose each of the pawls is provided with a lug such as shown at 31^a, which is adapted to be engaged by the treadle for the purpose of throwing the pawl.

The equalizing member 23 to which reference has before been made has secured there to one end of a spring 33 the opposite end of which is conveniently secured upon the underside of the table 1, as indicated at 34.

From the foregoing description it will be seen that pressure applied at any portion of the treadle member 29 will depress this treadle member and will cause a turning movement of the shaft 26 because each of the arms 27 and 28 are secured to this shaft, and therefore depression of either or both of these arms will cause rotation of the shaft 26. This will in turn cause the arm 25 to be depressed, and inasmuch as the arm 25 is in substantially the middle portion of the shaft 26 practically equal application of turning movement to the arm 25 will be applied whether the treadle member 29 be depressed at one end or at both ends.

Movement of the arm 29 will move the equalizing member 23 which in turn will exert a pull upon the rods 21 and 22, and this in turn will depress the arms 19 and 20, causing turning movement of the shafts 17 and 13 respectively, which will move the arms 12 and 12^a, and so lift the roller member 11 into contact with the ironing member 6.

When the treadle member is released the spring 33 will restore the various parts which have been described to the position in which they are inactive.

The equalizing member 23 will cause an equal application of pressing force all along the roll 11, even though the roll may not be moved as close to the ironing member at one part thereof as it is at another. For instance, suppose that an article of some thickness, as for instance, a doubled Turkish towel, were inserted at one end of the roll, and a handkerchief were inserted at the other end of the roll, both being inserted simul-

taneously. The thicker article would naturally hold the roller member 11 further from the ironing member 6 than would the thin article, but nevertheless, the pressure which is applied is the same in both instances, because the pressing action on the treadle 27 is through the arm 29 delivered to the equalizing member 23, and this force is applied equally to both of the rods 21 and 22, and through the various connecting instrumentalities to each end of the roller member 11. If one end of the roller member 11 can not move so close to the ironing member as the other this is compensated in the equalizing member 23, but the pressure which is exerted will be the same at all parts of the roll.

Having described my invention, I claim:—

1. In combination in an ironing machine, an ironing member, a co-operating roller member, means for moving one of said members toward the other comprising independent arms which support the movable member at opposite ends thereof, a movable actuating member, connections between said actuating member and each of said arms including an equalizing mechanism whereby the engaging pressure of said members is uniform.

2. In combination, in an ironing machine, an ironing member, a co-operating roller member, means for moving one of said members toward the other comprising independent arms which support the movable member at the ends thereof, a movable actuating member, an equalizing member with one point of which the actuating member is connected, each of said arms being operatively connected with opposite points of the said equalizing member whereby the engaging pressure of said members is uniform.

3. In combination in an ironing machine, an ironing member, a co-operating roller member, means for moving one of said members toward the other member comprising independent arms which support the movable member at the opposite ends thereof, a movable actuating member, an equalizing member, means connecting the actuating member with the equalizing member in the central portion thereof, and means connecting each of said arms with the equalizing member upon opposite sides of its connection with the actuating member.

4. In combination in an ironing machine, a supporting frame, an ironing member, a co-operating roller member, means for moving one of said members toward the other member comprising independent arms which support the movable member at the opposite ends thereof, a movable actuating member, an equalizing member, means connecting the actuating member with the equalizing member in the central portion thereof, and means connecting each of said arms with the equal-

izing member upon opposite sides of its connection with the actuating member, and a spring connection between the equalizing member and frame.

- 5 5. In combination in an ironing machine, an ironing member and a co-operating roller member, means for moving one of these members toward the other comprising independent arms which support the opposite 10 ends of the movable member, independent shafts upon which each of said arms are mounted, arms independently connected to each of the said shafts, an equalizing member, each of said last mentioned arms being 15 connected with the equalizing member, a movable actuating member, and means connecting the actuating member with said equalizing member.
- 6 6. In an ironing machine, an ironing member, a co-operating roller member, means for moving one member toward the other comprising arms which support the movable member at the opposite ends thereof, a movable actuating member, a pair of arms to one 20 end of which said actuating member is connected, the opposite ends of said arms being mounted on a shaft, an equalizing member, means connecting a central portion of the 25

equalizing member with said shaft, and means connecting opposite points upon said 30 equalizer with the arms which support the roller member.

- 7 7. In combination in an ironing machine, an ironing member, a co-operating roller member, means for moving one member toward the other comprising arms which support the movable member at the opposite 35 ends thereof, a pair of aligned but independently rotatable shafts, one of said arms being secured to each of said shafts, another 40 arm secured to each of said shafts, an equalizing member, rods connecting each of the second mentioned arms with points on the equalizer member which are oppositely disposed with respect to the central portion of 45 the equalizing member, a movable actuating member, arms at the ends of which said actuating member is mounted, a shaft on which said arms are mounted, a single arm mounted at substantially the central portion of the last mentioned shaft and connected with a central portion of the equalizing member for the purpose described.

In testimony whereof, I hereunto affix my signature.

EARL B. DECKER.
